2 SHEETS—SHEET 2.

UNITED STATES PATENT OFFICE.

WILLIAM E. MOORE, OF PITTSBURGH, PENNSYLVANIA.

FURNACE-CHARGING APPARATUS.

1,304,351

Specification of Letters Patent. Patented May 20, 1919.

Application filed August 24, 1917. Serial No. 183,048.

To all whom it may concern:

Be it known that I, WILLIAM E. Moore, a citizen of the United States, residing at Pittsburgh, in the county of Allegheny and 5 State of Pennsylvania, have invented certain new and useful Improvements in Furnace-Charging Apparatus, of which the following is a specification.

The machine comprising this invention 10 was devised primarily for the purpose of charging arc type electric furnace, wherein it is desired to deliver the raw material to the furnace in charging boxes brought up to the charging door of the furnace upon a 15 car, the boxes being removed from the car and inserted into the furnace through the charging door and there inverted so as to discharge material at various points on the furnace hearth, after which the box is withdrawn from the furnace and again deposited on the car, upon which it is transported back to the stock pile to be refilled.

One of the objects of this invention is to 20 provide an improved form of apparatus whereby these operations may be better performed, and which is of such a flexible character as to adapt it to perform other functions connected with the operation of the furnace.

Another object of the invention is to provide a charging mechanism which is located at a high point in the building over the 25 clearway necessary for the usual traveling crane, thus giving the maximum lift to the electrodes which usually determines the height of the furnace building where the electrodes are handled by means of a main traveling crane.

A further object of the invention is to so 30 pivot the crane part of the charging apparatus as to locate it immediately over the center of the door opening, thus automatically causing the charging box to enter through the doorway no matter into what 35 position the overhead crane may have been "slewed" to distribute the charge of the charging box on any desired position of the furnace hearth, thus reducing the liability of the operator injuring the furnace door 40 opening by ramming it with the charging box.

Other objects of the said invention will more readily appear from the following description, in which reference will be had to the accompanying drawings, wherein:

Fig. 1 represents in side elevation a form of apparatus embodying my invention;

Fig. 2 is a detail horizontal section of the charging box, supporting arm and parts immediately associated therewith;

Fig. 3 is a diagram illustrating different angular positions in a horizontal plane to which the charging box may be brought within the furnace;

Fig. 4 is a diagram showing a battery of 55 several furnaces and equipment according to my invention;

Fig. 5 is an enlarged section on the line 5x—5x of Fig. 1; and

Fig. 6 is a section on the line 6x—6x of 60 Fig. 2.

In the accompanying drawings, 1 represents an arc-type electric furnace; 2, the vertically movable electrodes; 3, the charging opening; 4, the charging door; 5, the 65 lintel or yoke of angle iron through which said door slides vertically and which extends outwardly therefrom; 6, the charging platform; 7, the charging car adapted to travel in front of the charging opening on 70 a track 8 located on said platform, and 9, the charging box in which the material is brought to the furnace and delivered thereto, said charging box being preferably curved or cylindrical in cross section, as 75 shown most clearly in Fig. 6. It is an advantage to make the charging box 9 cylindrical in cross section, as indicated, so that, when rotated on its axis, the charge which it contains may slide around inside the box 80 and permit the latter to rotate on its axis without having to overcome such resistance of the charge as would occur in the case where its center of gravity did not coincide with the center of rotation of the box. This 85 charging box comprises an elongated rectangular open topped metal structure, one of the sides of which has a tapered socket 10.

For the purpose of lifting the charging box from the car, inserting it into the furnace, rotating it on its longitudinal axis so 90 as to discharge its contents, and then with- 95

drawing it from the furnace and depositing it again on the car, there is provided, among other parts, an elongated arm or handle consisting of a cylindrical tube 11 having one end tapered, as at 12, to fit the tapered socket 10, said tube being closed at its tapered end by a plug 13 (see Fig. 2), rigidly attached thereto and having a screw-threaded central opening adapted to align 10 with a similar screw-threaded opening in the base of the socket 10.

For the purpose of binding the tapered end of arm 12 in the socket 10, there is provided a shaft or hollow rod 14, which extends longitudinally of the arm 11 parallel to its axis, and carrying at one end fast thereto a screw-threaded nipple, preferably of coarse pitch, or extension 15 adapted to revolve in the opening in the plug 13 and 20 screw into the base of the socket 10. The arm 11 and rod 14 are rotatable on their longitudinal axes by capstan wheels 16 and 17, the former having a hub 18 rigidly secured to the arm 11, and the latter (wheel 17) 25 having a hub 19 rigidly secured to a spindle or solid rod 20 rotatable in a bearing 21 in the hub of the wheel 16 and rigidly attached to the rod 14 or shaft. The arm 11 is rotatable on its longitudinal axis in two ball or 30 roller bearings 22 and 23, the housings of which are connected by a tubular brace 24 encircling the arm 11. The purpose of this tubular piece or brace is to prevent the above-mentioned bearings from being 35 warped out of position or alignment by the strains to which they are subjected in the operation of the apparatus.

The housing or bearing 22 is connected by a hinge 25, with its axis transverse to the 40 arm 11, to the lower end of a thrust rod 26 composed preferably of light weight pipe made of three sections so as to have a larger section in the middle of the thrust rod where the maximum bending movements occur, 45 and having its lower and upper ends attached by right and left hand screw threads, respectively, to a portion of the hinge 25 and to a trolley 28 mounted to travel on a crane jib 29 and so arranged as to take either 50 a downward pull or an upward thrust, as hereinafter more particularly described.

The housing of the forward bearing 23 is connected by a hinge 30 to the lower end of a hook 31 rearwardly bowed to clear the furnace door lintel when the arm 11 is pushed as far as possible into the furnace. The upper end of the hook 31 is adapted to hook into an eye or ring 32 on the lower end of a lifting rod 33, the upper end of which is 55 provided with an eye for engagement with a hook 34 on the end of a cable 35 of a motor hoist 36 also mounted to travel on said crane jib. Travel is imparted to the trolley 28 from the traveling motor hoist 36 through 60 a link connection 37 by which said trolley

and hoist may be connected together or disconnected at will. Suitable switches, push buttons, electric controls, and power circuits are provided for the motor hoist, but as these are well-known they need not be described in detail. I have, however, indicated a well-known form of rope control 38 for the propelling element of the motor hoist, and a similar control 39 for the hoisting element, these being in easy reach of the operator of wheels 16 and 17, as shown in Fig. 1.

The overhead crane for lifting the charging box and inserting it into the furnace comprises, among other parts, a double end jib composed of two parallel angle irons 29, U-shaped in cross section and held at suitable distance apart by yokes 29^a and 29^b. This jib is pivoted at points 32 and 33 for rotation in a horizontal plane. The axis of rotation 39^a of this jib, as shown most clearly in Fig. 3, coincides with the vertical center of the furnace door opening, thus insuring that the charging box will enter through the furnace doorway, no matter into what position the overhead crane may have been "slewed", to distribute the charge at the desired point on the furnace hearth, thus reducing the liability of the operator to injure the furnace door opening by ramming the charging box against it.

The pivots on which the above described jib is mounted are supported on the roof truss of the furnace building, said jib being provided in addition to yoke pieces 29^a and 29^b with suitable braces 40, 41 and 42, as shown. This jib is located above the track 43, now commonly employed to carry an electric traveling crane or hoist 44, which track usually extends the entire length of the furnace building.

In charging a furnace with my improved apparatus, a charging box is brought in front of the furnace opening on the charging car, the tapered end of the arm 11 inserted into the socket 10 and rigidly secured therein by the screw member 15 operated by capstan wheel 17, the drum of motor hoist 36 set in operation, and the charging box 9 lifted from the car. The motor hoist 36 is then caused to travel forward on the crane jib 29, whereby the charging box is inserted into the furnace, and by rotating the crane jib on its axis, this charging box may be brought to any one of several angular positions in the furnace, as shown most clearly in Fig. 3. Having inserted the charging box into the furnace in the proper position, its contents are discharged by rotating capstan wheel 16. After discharging the contents of the charging box, the travel of the motor hoist 36 is reversed, the box withdrawn from the furnace, re-deposited on the car, and the arm 11 disconnected from the charging box.

- When desired, the link connection between the trolley 29 and motor hoist 36 may be disconnected and the hook 34 disconnected from the rod 33, and the thrust rod 5 screwed from parts 25 and 28, thus freeing the motor hoist 36 and permitting it to be used for other purposes, such, for example, as hoisting the electrodes of the furnace and transporting them to a desired point.
- 10 When a battery of furnaces is employed, each furnace would preferably be provided with an individual charging mechanism and have a charging car track common to all of the furnaces, as shown in the diagram, Fig. 15 4. My invention also contemplates the employment, in a battery of furnaces arranged as above, of a charging box car arranged to travel on a track paralleling the row of furnaces in rear thereof, while the front of 20 said row of furnaces is served by an overhead traveling crane 45 for handling the ladles 46 containing molten steel or other metal, said crane being adapted to travel toward and away from the furnaces on overhead tracks 47 and provided with a suitable hoist 48.
- It will be understood that various modifications may be made in my invention as here shown and described without departing 36 from the spirit thereof.
- What I claim is:—
1. A furnace charging apparatus, comprising a support rotatably mounted on a vertical axis passing through the furnace charging opening, and charging means suspended from said support and movable toward and away from the furnace opening.
  2. A furnace charging apparatus, comprising a crane rotatably mounted on a vertical axis passing through the furnace charging opening, and adapted to swing in a horizontal plane, and charging means suspended from said crane and movable toward and away from the furnace opening.
  3. Mechanism of the class described, comprising a crane pivotally mounted to rotate in a horizontal plane above the furnace on an axis located directly over the vertical center of the furnace charging opening, a motor hoist mounted to travel thereon, a charging box supporting arm, and means to suspend said arm from said motor hoist.
  4. Mechanism of the class described, comprising a pivotally mounted crane, a motor hoist mounted to travel thereon, a charging box supporting arm, and means to suspend said arm from said motor hoist, said means including a rearwardly bowed hook adapted to space the lintel of the furnace door.
  5. Mechanism of the class described, comprising a pivotally mounted crane, a motor hoist mounted to travel thereon, a trolley also mounted to travel on said crane, detachable means to connect said trolley to said motor hoist, a charging box supporting arm,
- and means to suspend said arm from said trolley at one point and from said motor hoist at another point.
6. Mechanism of the class described, comprising a pivotally mounted crane, a motor hoist mounted to travel thereon, a trolley also mounted to travel on said crane, detachable means to connect said trolley to said motor hoist, a charging box supporting arm, a thrust rod connected to suspend said arm from said trolley at one point, and means including a cable from said motor hoist to suspend said arm at another point.
7. A furnace charging apparatus, comprising a crane rotatably mounted on a vertical axis passing through the furnace charging opening, and having a jib, a charging box, a supporting arm therefor, and means for suspending said supporting arm from said jib to permit the movement of the arm in a longitudinal direction toward and away from the furnace opening.
8. A furnace charging apparatus, comprising a crane rotatably mounted on a vertical axis passing through the furnace charging opening, and having a jib, a supporting arm carried by said jib and movable longitudinally thereof toward and away from the furnace charging opening, a detachable box carried by said supporting arm at the end adjacent to the furnace, and means carried by the opposite end of the arm causing the rotation of the box to empty the contents thereof.
9. Mechanism of the class described, comprising, in combination with a furnace charging box having a tapered socket, a hollow arm adapted to extend at one end into said socket, and a screw rod extending axially through said arm and adapted to bind said arm in said socket.
10. Mechanism for charging furnaces, comprising a pivotally mounted crane, a motor hoist mounted to travel thereon and provided with a hoisting cable, a trailer comprising a trolley also mounted to travel on said crane, means to detachably connect said trailer to said motor hoist, a charging box arm, a thrust rod having one end connected to said trolley, a bearing in which said arm is rotatably mounted, means to flexibly connect said bearing to the lower end of said rod, a second bearing in which said arm is rotatably mounted and located between the first bearing and the charging box engaging end of said arm, a lifting rod connected to said last-mentioned bearing, and a brace connecting the housings of said bearings.
11. Mechanism for charging furnaces, comprising a crane mounted to rotate in a horizontal plane above the furnace, a motor hoist mounted to travel on said crane and provided with a hoisting cable, a trailer comprising a trolley also mounted to travel on said crane, means to connect said trailer to

5 said motor hoist, a charging box supporting arm, a thrust rod having one end connected to said trolley, a bearing in which said arm is rotatably mounted, means to flexibly connect 10 said bearing to the lower end of said rod, a second bearing in which said arm is rotatably mounted and located between the first bearing and the charging box engaging end of said arm, a hook bowed rearwardly to receive the lintel of the furnace door and hinged to the second-mentioned bearing, and a lifting rod secured to said hook and cable.

15 12. A furnace charging apparatus, comprising a bearing, a cylindrical supporting arm rotatably mounted in said bearing, and being provided with a tapered end, a charging box having a socket arranged to receive the tapered end, a rod mounted for rotation 20 within said cylindrical arm, fastening means carried by said rod at one end for securing said charging box, and means carried by the opposite end of said rod for actuating said securing means.

25 13. A furnace charging apparatus, comprising a bearing, a cylindrical supporting arm rotatably mounted in said bearing, and being provided with a tapered end, a charging box having a socket arranged to receive the tapered end, a rod mounted for rotation 30 within said cylindrical arm, a screw carried by said rod at one end for securing said charging box, and a handle at the opposite end of the rod for actuating said screw.

35 14. Furnace charging apparatus comprising a charging box and a supporting structure therefor mounted to have swiveling mo-

tion on a vertical axis adjacent the furnace charging opening in any position of said charging box.

40 15. Furnace charging apparatus comprising a charging box and a supporting structure therefor mounted to have swiveling motion on a vertical axis coinciding substantially with the vertical center of the furnace 45 charging opening.

16. Furnace charging apparatus comprising a charging box and a supporting structure therefor mounted to have swiveling motion in a vertical axis adjacent the furnace 50 charging opening in any position of said charging box, and a horizontal movement to insert and withdraw the charging box into and from the furnace.

55 17. A furnace charging apparatus, comprising a crane pivotally mounted on a vertical axis, passing through the center of the furnace charging opening, a motor hoist mounted to travel thereon, a trolley having a detachable connection with said motor hoist, a charging box supporting arm, a thrust rod connected with said trolley and having a hinged connection with said supporting arm, means, including a cable, for suspending said supporting arm at a point 60 intermediate of the thrust rod and the furnace, a detachable charging box carried by said supporting rod, and means carried by said arm and operable at the end opposite the charging box for inverting said charging box and for detaching it from said arm.

65 In testimony whereof I affix my signature.

WILLIAM E. MOORE.
